UNITED STATES PATENT OFFICE.

SILAS B. TERRY, OF WATERBURY, CONNECTICUT.

DESIGN FOR CLOCK-FRONTS.

Specification forming part of Design No. 7,850, dated November 10, 1874; application filed September 4, 1874.
[Term of Patent 14 years.]

To all whom it may concern:

Be it known that I, SILAS B. TERRY, of Waterbury, in the county of New Haven and State of Connecticut, have invented a new Design for Clock-Front; and do hereby declare the following, when taken in connection with the accompanying drawings and the letters of reference marked thereon, to be a full, clear, and exact description of the same, and which said drawings constitute part of this specification, and represent, in—

Figure 1, a front view; Fig. 2, vertical central section.

This invention relates to a design for the front or sash of a clock-case, commonly called "clock-fronts," the object being to produce a swell or projecting front; and it consists in a swell-front produced by a slightly-raised plain edge around a reversed ogee-frame, as more fully hereinafter described, and as shown in the accompanying illustration.

The outline of the case is immaterial to the design, but for illustration is here shown as octagonal. The outer edge, *a*, is a plain fillet, slightly raised from the inner adjoining surface, as seen in Fig. 2. From this edge or border, inward, the surface *A* of the front rises in a reversed ogee form, swelling to the inner edge, where the glass is set. This gives to the front a novel and pleasing effect.

I claim—

The herein-described design for clock front or sash, consisting of the raised edge *a*, and swelling to the sight or inner edge in a reversed ogee surface, *A*, as shown in the accompanying illustrations.

SILAS B. TERRY.
